ILLUMINATING FIXTURE

Edwin F. Guth, St. Louis, Mo.

Application October 30, 1939, Serial No. 301,969

1 Claim. (Cl. 240—78)

This invention relates to illuminating fixtures, and with regard to certain more specific features, to electrical illuminating fixtures.

Among the several objects of the invention may be noted the provision of an electric illuminating fixture of the direct-indirect type, which is highly efficient in the manner in which it distributes portions of the light both upwardly for indirect illumination and downwardly for direct illumination; the provision of a fixture of the class described which, in operation, has no objectionably glaring or brilliant surfaces when viewed from any normal position of an observer; and the provision of a fixture of the class described which is relatively simple and economical to construct. Other objects will be in part obvious and in part pointed out hereinafter.

The invention accordingly comprises the elements and combinations of elements, features of construction, and arrangements of parts which will be exemplified in the structures hereinafter described, and the scope of the application of which will be indicated in the following claim.

In the accompanying drawings, in which are illustrated several of various possible embodiments of the invention,

Fig. 1 is a side elevation, partly in axial section, of a fixture embodying the present invention;

Fig. 2 is a horizontal cross-section taken substantially along line 2—2 of Fig. 1;

Fig. 3 is a view similar to Fig. 1, showing a second embodiment of the invention;

Fig. 4 is a view similar to Fig. 1, illustrating a third embodiment of the invention; and,

Fig. 5 is a view similar to Fig. 1, illustrating a fourth embodiment of the invention.

Similar reference characters indicate corresponding parts throughout the several views of the drawings.

Referring now more particularly to Fig. 1, numeral 1 indicates the usual stem or tube by which the fixture of the present invention is supported, as from the ceiling. At its lower end the stem 1 carries a socket 2, which is surrounded by a husk or socket cover 3, in the usual manner. Numeral 4 indicates an electric light bulb, of the usual pear-shaped form, which has an integral silvered reflecting portion 5 at its lower, hemispherical end. It will be pointed out hereinafter that the silvered reflecting portion 5 need not be integral with the bulb, but for the time being the invention will be described in its embodiment using such a bulb.

Numeral 6 indicates an upwardly-facing bowl-

shaped or annular reflector of the type generally used in indirect illuminating fixtures. The particular conformation of this reflector 6 is not the subject of the present invention; the present invention may be adapted with facility to substantially any form of indirect reflector of this general category. However, the reflector 6 of the present invention differs in that it is open across substantially its entire bottom, as indicated at numeral 7.

Numeral 8 indicates an annular reflector element that constitutes one of the characteristic features of the present invention. The reflector element 8 is a ring, curved in cross-section, with a central opening 9 at its upper end, which is its end of lesser diameter. The reflector 8 is concave downwardly. The lower, outer end of the reflector 8, being the end of greatest diameter, is secured by rivets 10, or other suitable means, to the side walls of the reflector 6, so that the reflectors 6 and 8 are in relatively permanent assembly. In the embodiment of the invention now being described, the opening 9 in the top of the reflector 8 is of considerably larger diameter than the maximum diameter of the bulb 4, so that the reflector assembly easily passes over the bulb 4. The top of reflector 8 is spaced a short distance above the upper edge of silvered reflecting portion 5, this distance 20 preferably being adjustable in a manner hereinafter to be described.

The under or concave surface of the reflector 8 is preferably highly polished, so that it is a substantially specular reflector. The inner or concave surface of the reflector 6, on the other hand, may be and usually is diffusely reflective. The reflective character of the reflector 6 above the reflector 8 is of little moment to the present invention.

Slipped into suitable key-hole shaped openings 21 along the upper edge of the reflector 8 are the lower headed ends 20 of wires 11, the upper hooked ends 22 of which are engaged in suitable openings in the lower edge of the husk 3. The key-hole shaped openings 21 have lower portions of sufficient size to pass the heads 20 of wires 11, and upwardly extending portions of smaller width sufficient to pass wires 11 but not heads 20. In this manner the reflector assembly is supported in proper axial position, relative to the bulb 4, from the husk 3. Ordinarily three such wires 11 are sufficient properly to achieve this support.

The openings 21 are preferably near the upper edge of reflector 8. One or more additional rows

of similar openings 23 are preferably provided somewhat down the side of reflector 8. The openings 23 may be used alternatively to the openings 21, thus to adjust the relative vertical dispositions of the fixture and its bulb, and consequently to vary the proportions of light reflected upwardly and reflected downwardly. Other means can of course be provided in place of the alternatively-used rows of openings, for securing the same adjustment effect.

The fixture as thus constructed affords, in operation, an excellent combined direct and indirect illumination. The silvered portion 5 of the bulb 4, it will be understood, is opaque, so that no light whatsoever escapes downwardly directly from the bulb 4. On the contrary, all of the light in the bulb 4 is directed upwardly throughout a substantial hemisphere the bounding plane of which is at the bottom and substantially horizontal. Part of this light is intercepted by the specular reflecting surface of reflector 8, and reflected downwardly through the opening 7 of reflector 6 to afford direct illumination. Ordinarily the fixture is so designed that this downwardly reflected light does not constitute more than the order of 25% of the total light, but this proportion may be varied by adjustment of the relative positions of the fixture and bulb, as hereinbefore indicated. The remainder of the light, which is not intercepted by reflector 8, is directed upwardly against the ceiling, with the aid of the inner surface of reflector 6, to afford the desired indirect illumination.

The proportion of emitted light used for the direct illumination afforded by the reflector 8 may also be varied within wide limits, by varying the curvature in cross section, as well as by varying the axial position of said reflector 8.

A notable feature of the fixture of the present invention is that to an observer looking upwardly at the fixture, from any position other than one almost immediately under it, there is no objectionable glare or brilliance on any of the fixture parts as a result of the means provided for direct illumination. The observer, of course, cannot see the light source directly, because of the opaque nature of the silvered region 5 on the bulb 4. The curvature of the reflector 8 is such that substantially all of the light rays are directed downwardly in a cone of gradually increasing diameter. The reflector 8 reflects substantially no light against the inner surface of the reflector 6 therebeneath, and such inner surface, which is the only one ordinarily visible to the observer looking at the fixture, consequently is not objectionably brilliant or glary. In other words, that portion of the inner surface of reflector 6 below the reflector 8 is substantially in shadow at all times.

Fig. 3 illustrates a modification of the invention wherein the wires 11 are dispensed with. In this modification the opening 9^a in the top of reflector 8^a is made slightly less in diameter than the maximum diameter of the bulb 4; the fixture assembly comprising reflectors 6 and 8^a is then supported, in operation, by hanging it directly on the bulb 4. It will be noted that in this embodiment, as well as in the prior embodiment, the upper edge of the reflector 8^a is again positioned somewhat above the upper edge of the silvered portion 5 of the bulb 4, so that light for direct illumination can reach the specular reflecting concave surface of reflector 8^a.

Fig. 4 illustrates another modification where the reflector 8^b is a separate piece, shaped sub-

stantially as heretofore, but in this instance cast from a refractory material such as glass and then silvered to present a mirror surface on its lower face 24. The reflector 8^b of this embodiment rests freely on an annular shoulder 25 formed in the side wall of reflector 6^a. The lower ends of wires 11, in this embodiment, hook into suitable brackets 26 on the inner surface of reflector 6^a.

10 The invention does not necessitate the use of a bulb with an integrally included silvered portion 5, as has heretofore been suggested. Fig. 5, for example, illustrates an embodiment of the invention suitable for use with a bulb (indicated by numeral 12) that is formed of transparent or translucent glass throughout. In this embodiment, a discrete hemispherical reflector element 13, such as a thin metal hemisphere, the inner surface of which is polished or silvered to be substantially specularly reflecting, is fitted closely around the lower end of the bulb 12. Supporting strips 14, or other suitable means, support this hemispherical reflector 13 from the upper edge of the reflector 8^c. The remainder of the fixture of Fig. 5 is substantially identical to the fixture of Fig. 1. It will readily be seen that in this instance the discrete reflector 13 functions in almost an identical manner to the integral silvered reflector portion 5 of the bulb 4 in the Fig. 1 embodiment.

30 A principal advantage of all of the embodiments of the invention thus described is the ease and economy with which they may be manufactured, and, in most instances, serviced with a new lamp (through the opening). Substantially no parts are required that cannot be readily produced by a simple spinning operation. There are substantially no parts of irregular shape or conformation, and the assembly of the fixture is a simple operation, requiring substantially no particular skill on the part of the worker. Nevertheless, the fixture is a highly efficient one, and one which presents a pleasing, ornamental appearance.

45 In view of the above, it will be seen that the several objects of the invention are achieved and other advantageous results attained.

As many changes could be made in the above constructions without departing from the scope 50 of the invention, it is intended that all matter contained in the above description or shown in the accompanying drawings shall be interpreted as illustrative and not in a limiting sense.

I claim:

55 An electric illuminating fixture comprising an electric light bulb, socket means receiving and mounting said bulb, and a reflector assembly surrounding said bulb comprising hemispherical reflecting means at the hemispherical end portion of said bulb and adapted to reflect light toward the socket, a first annular reflector facing the socket and surrounding the bulb but spaced therefrom, and a second annular reflector 60 facing away from the socket and between the bulb and said first reflector, said second reflector having an inner edge axially nearer the socket than the edge of said hemispherical reflecting means, said second reflector having a substantially specular concave reflecting surface facing away from said socket, said first and second reflectors being secured together in a relatively permanent manner, with a portion of the first reflector extending axially beyond the second reflector in both directions, the portion of the inner surface of said first reflector that extends

beyond said second reflector in an axial direction away from said socket having a non-specular reflective character, the curvature of the second reflector being such that light rays from the bulb are generally reflected by said second reflector in a divergent manner and in such manner as to avoid lighting the aforesaid portion of the

inner surface of the first reflector beyond the second reflector in a direction away from the socket, and means for adjusting the relative vertical positions of said bulb and said reflector assembly for varying the proportions of light reflected towards and away from said socket.

EDWIN F. GUTH.
